[57] ABSTRACT

An oscillating circuit comprising a Schmitt circuit, a grounded capacitor connected to the input side of the Schmitt circuit and a control circuit connected to the output side of the Schmitt circuit for controlling the charging and discharging of the capacitor.

FIG. 1

FIG. 2

FIG. 3

OSCILLATING CIRCUIT

FIELD OF THE INVENTION

This invention relates to oscillating circuits and, more particularly, an oscillating circuit using a Schmitt circuit which may be readily integrated into a semiconductor integrated circuit and may be made to serve as a variable oscillator.

SUMMARY OF THE INVENTION

An object of the invention is to provide an oscillating circuit comprising a Schmitt circuit, a grounded capacitor connected to the input side of the Schmitt circuit and a transistor control circuit connected to the output side of the Schmitt circuit for controlling the charging and discharging of the grounded capacitor.

BRIEF DESCRIPTION OF THE DRAWING

FIG. 1 is a circuit diagram showing an embodiment of the oscillating circuit according to the invention.

FIG. 2 shows a hysteresis character of the oscillation of the circuit of FIG. 1.

FIG. 3 is a graph showing the terminal voltage across the charging and discharging capacitor.

DESCRIPTION OF THE PREFERRED EMBODIMENT

FIG. 1 shows a preferred embodiment of the oscillating circuit according to the invention. It uses a Schmitt circuit including transistors TR₁, and TR₂ and resistors R₂, R₃ and R₅. A grounded capacitor C₁ is connected to the input side of the Schmitt circuit. The charging and discharging of the capacitor C₁ is controlled through a circuit consisting of a transistor TR₃, resistors R₅ and R₆ and a diode D₁. It is discharged through a discharging resistor R₁. The resistor R₂, R₃ and R₅ are connected to a power supply V_{cc}.

In the operation of the circuit described above, when the transistors TR₁, TR₂ and TR₃ are respectively off, on and off, the capacitor C₁ is charged through the loop of power source V_{cc}, resistors 5 and 6 and capacitor C₁. At this time, the voltage drop V across the resistor R₄ is

$$V = R_4 / (R_4 + R_3) \cdot V_{cc},$$

(ignoring the saturation voltage of the transistor TR₃). Thus, the terminal voltage across the capacitor C₁ reaches a predetermined value given as

$$V_c = R_4 / (R_4 + R_3) \cdot V_{cc} + V_{BE} \quad (1)$$

(where V_{BE} is the potential difference between the base and emitter of the transistor TR₂). As soon as this predetermined terminal voltage across the capacitor C₁ is reached, the transistor TR₁ is triggered. At this instant,

$$V_c \geq R_4 / (R_4 + R_3) \cdot V_{cc} + 0.6 V \quad (2)$$

(where 0.6 V represents the potential difference between the base and emitter of the transistor TR₁). Also, for the base voltage on the transistor TR₁ at this instant

$$R_4 / (R_2 + R_4) (V_{cc} - V_{CE}) - V_{BE} \geq V_c \quad (3)$$

(where V_{CE} is the potential difference between the collector and emitter of the transistor TR₁ and equal to the base-emitter voltage thereof). Upon triggering of the transistor TR₁, the transistor TR₂ is cut off to trigger the transistor TR₃.

At this time, if Z₁ < Z₂ < Z₃ where Z₁ is the impedance provided by resistor R₆, transistor TR₃ and diode D₁, Z₂ is the impedance provided by resistor R₁, and Z₃ is the impedance provided by transistor TR₁ and resistor R₄, the capacitor C₁ is discharged through a loop of resistor R₆, transistor TR₃ and diode D₁ and through another loop of resistor R₁.

As soon as the terminal voltage of the capacitor C₁ being discharged is reduced to a certain prescribed level, the transistor TR₁ is cut off, triggering the transistor TR₂ to cut off the transistor TR₃. As a result, re-charging of the capacitor C₁ starts.

If the resistance of the resistor R₂ is equal to the resistance of the resistor R₃, the charging and discharging of the capacitor C₁ take the same period. However, if the former resistance is selected to be greater than the latter resistance, the base potential of the transistor TR₁ at the instant of its triggering is different from the level at the instant of its cut-off. Thus, the oscillation involves a hysteresis decay as shown in FIG. 2.

In this case, the capacitor C₁ is charged and discharged in a manner as shown in FIG. 3. In the Figure, V₁ and V₂ represent respective minimum and maximum levels of the terminal voltage across the capacitor C₁, and from equations 2 and 3

$$V_1 = R_4 / (R_2 + R_4) \cdot (V_{cc} - V_{BE}) \quad (4)$$

and

$$V_2 = R_4 / (R_2 + R_4) \cdot V_{cc} + V_{BE} \quad (5)$$

The resistor R₁ serves to stabilize the discharging of the capacitor C₁ and hence the oscillation of the oscillating circuit according to the invention. Without the resistor R₁, the discharging of the capacitor C₁ through the path of resistor R₆, transistor TR₃ and diode D₁ is likely to be suddenly subjected to very unstable conditions.

As has been described, according to the invention a hysteresis character is imparted to the operation of the Schmitt circuit for on-off controlling the control transistor TR₃ controlling the charging and discharging of the capacitor C₁, so that reliable oscillation can be ensured. Also, all the components parts which are relatively small in number may be readily integrated into a semiconductor integrated circuit except for the capacitor C₁. Further the oscillation frequency may be readily made variable by using a variable capacitor for the capacitor C₁.

We claim:

1. An oscillating circuit comprising a Schmitt circuit including a pair of transistors connected in cascade, a capacitor connected between the input of said Schmitt circuit and ground, a control transistor coupled to the output of said Schmitt circuit for controlling the charging and discharging of said capacitor, the on-off operation of said control transistor being controlled by the output of said Schmitt circuit, connecting circuit means connected between said capacitor and said control transistor, said connecting circuit means being a portion of a charging circuit and also a portion of a first discharge circuit, a second discharge circuit for said capacitor including a resistor connected in parallel with said capacitor, and

a diode connected in series with said control transistor, said connecting circuit means, control transistor and diode comprising said first discharge path, said first discharge path having a low impedance with respect to the impedance of said second discharge circuit.

UNITED STATES PATENT OFFICE
CERTIFICATE OF CORRECTION

Patent No. 3,731,228 Dated May 1, 1973

Inventor(s) Noriyoshi Kubo et al

It is certified that error appears in the above-identified patent and that said Letters Patent are hereby corrected as shown below:

Col. 2, line 31, formula should read:

$$V_2 = R_4 / (R_3 + R_4) V_{CC} + V_{BE}$$

Signed and sealed this 27th day of November 1973.
